JOSEPH H. TRYON, OF GLEN RIDGE, NEW JERSEY, AND CHARLES A. GROTH, OF OZONE PARK, NEW YORK.

METHOD OF MAKING PRINTING PLATES.

1,100,854.

Specification of Letters Patent. Patented June 23, 1914.

Application filed March 6, 1914. Serial No. 822,864.

To all whom it may concern:

Be it known that we, JOSEPH H. TRYON, a citizen of the United States, and a resident of Glen Ridge, in the county of Essex and State of New Jersey, and CHARLES A. GROTH, a citizen of the United States, and a resident of Ozone Park, in the county of Queens and State of New York, have jointly invented a certain new and useful Method of Making Printing-Plates, of which the following is a specification, taken in connection with the accompanying drawing, which forms a part of the same.

This invention relates to the method of making printing plates and more particularly to a method of making a printing plate from a relief surface.

Our invention further relates to forming a printing plate directly from a photo engraved process plate, or ordinary half-tone plate, without the aid of transfer. And, further, to the method of making a single printing plate by accurately positioning a plurality of printing surfaces on the plate and making a record for duplication of the printing plate.

Our printing plates may be used in the ordinary off set printing press to print either black and white, or preferably, colored lithographs.

Figure 1 is a diagrammatic view in vertical section; Fig. 2 is a plan view of one of our printing plates having a plurality of printing surfaces properly spaced with relation to each other, the spacing being recorded.

Prior to our invention, it has been the practice to build up a printing surface for the ordinary offset method in printing lithographs by using the ordinary paper transfers. Such transfers, which are well-known in the art and need not be elaborated here, make a printing surface which is at least two steps removed from the original half-tone or other original relief printing plate. With the printing plate so many steps removed from the original, it has been found impossible to reproduce all the fine and artistic finish and personal characteristics of the artist which show for example, on the photo-engraved process half-tone plate. Moreover, the present method of requiring paper transfers, entails the expense of lithographic artists to touch up and correct, as far as they can, the transfers and also re-

quires the services of a lithographic transfer. The old method requiring transfer is, therefore, not only removed two steps from the original, with the consequent inferior artistic finish, but is also more expensive than our improved method.

We take a relief printing surface which may be type, a wood cut, a zinc etching, or a similar printing surface, but is preferably and ordinarily, a half-tone plate made by the ordinary photo-engraved process which reproduces all the fine and artistic work of the artist, as well as his personal artistic characteristics, which are well understood and recognized by those familiar with the work of any particular artist. This relief plate we put into a press of any suitable description, and obtain our printing plates directly from the original without paper transfers, so that our method is direct and is not one which is twice removed from the original as is the old method requiring the use of a paper transfer. We have found in practice that perfect results are obtained by placing the half-tone relief plate 1 on a bed, 2, inking it, and placing directly over and in contact with it a zinc, aluminum or other printing plate 3. Over the plate 3, we place a plate of harder material than that plate so as to prevent the plate 3 becoming embossed. We, preferably, make this plate 4 of steel. Above the steel plate is placed a resilient member, such for example, as a rubber pad 5. The plate 8 of the press may bear directly upon the resilient member or rubber pad 5, but preferably we use an interposed pad of paste board 7 or thin wood. The plates referred to, are then subjected to pressure. Preferably, they are placed in a hydraulic press having a platen 8 where the pressure can be instantly regulated and observed through a suitable dial for the pressure will vary for different jobs. We have obtained perfect results with a pressure of 90

2 to 12 tons, although in many instances the pressure may be below this in some class of work and far in excess of it in others, all depending upon the particular job.

The printing plate 3 is preferably slightly grained before subjecting it to the action of the hydraulic press, so as to give the printing plate 3 a "tooth" to hold the ink. This graining of the plate may be subsequently coarsened by chemical means well-known in the art. While we preferably use 110

a slightly grained plate, such for example, as the zinc or aluminum plate, we may in some cases use a smooth plate, and subsequently grain it, although the former we 5 consider preferable. The printing plate 3 will be a positive and when suitably treated with water and ink in the well-known offset lithographic process will give perfect impressions of the original half-tone plate, or 10 other relief surface from which it is obtained directly.

While printing plates may be used separately, as above described, for black and white work, our method is particularly 15 adapted for colored lithographic work.

As is well-known in the art of three color process work, three photo-engraved plates of each picture are made of the primary colors, yellow, red and blue. When particularly 20 fine work is required an additional or black plate is made, making four plates in all. By our method we obtain a printing plate 3 from each one of the three primary half-tone plates, or four, if a black plate is made, a separate 25 zinc, aluminum or other plate 3 being placed in direct contact, one at a time, with the three or four primary half-tone plates. Therefore, for the reproduction of each colored lithograph, we have at least three 30 printing plates 3, or four such plates, if a black plate is used, each plate, of course, being made directly from its own original relief plate 1 without the aid of a transfer. These plates are then further grained by 35 well-known chemical means if necessary, subjected to water and their own particular colored ink in the ordinary offset lithographic printing process and form a complete and perfect reproduction in colors of 40 the original by printing severally, one above the other, as is well-known in that branch of the offset printing art.

The printing plate 3, after an impression, is removed from the face of the relief plate 45 or half-tone 1 to permit the half-tone to be again inked, when the printing plate 3 is adjusted to present a new portion of its surface to the original relief plate 1 when pressure is again applied and a second printing 50 surface 9 is made upon the plate 3. This is repeated as often as may be desired to obtain the necessary number of printing surfaces 9, 9 on the plate 3, each position being accurately noted and recorded to permit a 55 duplicate printing plate 3 to be made at any time, if desired, without a new layout sheet. One apparatus for carrying out our method is shown and described in our companion application filed of even date herewith, 60 Serial No. 822,865 to which attention is directed.

The printing surfaces 9, 9 may be from the same original relief printing plate or from different relief printing plates as desired, it 65 not being essential that all the printing sur-

faces 9, or any one printing plate 3 be duplicates though in practice such ordinarily would be the case. We may also use an overlay 10 preferably under or over the rubber sheet 5 and next to the steel plate 4 or over the rubber. An ordinary underlay 11 may also be used in some cases under the relief printing plate 1. These overlays 10 and underlays 11 would seldom be used and, of course, may be omitted without in any manner affecting our improved method.

Having thus described this invention, in connection with an illustrative embodiment thereof, to the details of which we do not desire to be limited, what is claimed as new and what it is desired to secure by Letters Patent is set forth in the appended claims.

1. The method of forming a printing surface from a relief surface consisting in inking the relief surface, placing a sheet metal surface directly in contact with the relief surface, backing the sheet metal surface with harder material than the sheet metal surface, and applying a yielding pressure to said harder material whereby the said surfaces are brought into uniform contact throughout and a uniform impression is imparted directly to the printing surface without a transfer and without embossing the printing surface.

2. The method of forming a printing surface from a relief surface consisting in inking the relief surface, placing a grained sheet metal surface directly in contact with the relief surface, backing the sheet metal surface with harder material than the sheet metal surface, and applying a yielding pressure to said harder material whereby the said surfaces are brought into uniform contact throughout and a uniform impression is imparted directly to the printing surface without a transfer and without embossing the printing surface, and subsequently further graining the printing surface to hold more water.

3. The method of forming a printing surface on metal consisting in taking a metal plate having a relief surface, inking it, superimposing a sheet of metal directly in contact with the metal surface of the printing plate, and subjecting the metal printing plate and metal sheet to an abnormal pressure to obtain on the metal sheet a printing surface directly from the original without transfer and without embossing the printing surface.

4. The method of forming a printing surface on metal consisting in taking a metal plate having an integral metal relief surface, inking it, superimposing a sheet of metal directly in contact with the metal surface of the printing plate, and subjecting the metal printing plate and metal sheet to an abnormal pressure to obtain on the metal sheet a printing surface directly from the

original without transfer and without embossing the printing surface.

5. The method of forming a printing surface on metal consisting in taking a metal plate having a relief surface, inking it, superimposing a sheet of metal directly in contact with the metal surface of the printing plate, and subjecting the entire metal printing plate at one time to pressure to obtain 10 on the metal sheet a printing surface directly from the original without transfer and without embossing the metal plate.
6. The method of forming a printing surface on metal, consisting in taking a metal plate having a relief surface, inking it, superimposing a sheet of grained metal directly in contact with the metal surface of the printing plate, and subjecting the metal printing plate and the grained metal sheet 15 to pressure to obtain on the grained metal sheet a printing surface directly from the

original without transfer and without embossing the printing surface and subsequently further graining the grained metal sheet to hold more water.

25

7. The method of forming a printing surface on metal, consisting in taking a half tone plate having a relief surface, inking it, superimposing a sheet of metal directly in contact with the metal surface of the half tone plate and subjecting the half tone plate and metal sheet to pressure to obtain on the metal sheet a printing surface directly from the original half tone plate without transfer and without embossing the printing 30 surface.
